SLITTING MACHINE

Robert McC. Johnstone, Bondsville, Pa.

Application January 30, 1942, Serial No. 428,957

9 Claims. (Cl. 164—65)

A principal object of this invention is to provide improved means for mounting, tensioning and adjusting slitter elements in a slitting machine.

More specifically, one object of the invention is to provide means for facilitating the insertion and removal of the slitter units in and from the machine.

Another specific object of the invention is to provide improved means for advancing and retracting the slitter elements into and from operative engagement with the platen roll, and for adjusting the pressure of the elements against the platen.

A further specific object of the invention is to provide, in conjunction with said advancing and retracting means, an improved device for smoothing the work material on the platen preparatory to the slitting operation.

The invention resides further in certain novel structural and mechanical details hereinafter described and illustrated in the attached drawings, in which:

Figure 1 is a view in perspective of a slitting and rewinding machine made in accordance with my invention;

Fig. 2 is an enlarged fragmentary side elevational view of the machine;

Fig. 3 is a section on the line 3—3, Fig. 2;

Fig. 4 is a section on the line 4—4, Fig. 3;

Fig. 5 is a section on the line 5—5, Fig. 3;

Fig. 6 is a section on the line 6—6, Fig. 4, and

Fig. 7 is a fragmentary sectional view corresponding to Fig. 4 and showing certain parts of the mechanism in a different position of adjustment.

With reference to the drawings, the machine comprises the usual frame 1, in which are journaled front and rear winding drums, 2 and 3 respectively, said drums constituting the operating support for the roll 4 of the rewound and slit material, as illustrated. The work material, in the form in the present instance of a web 5, is drawn from a master roll 6 rotatably supported at the rear of the machine. The web passes around guide rolls 7 and 8, under the rear winding drum 3 to the front drum 2, and around the latter to the roll 4, this roll being started on a winding shaft 9 in well known manner. The front drum 2 constitutes a platen for the slitting operation, which is effected through the medium of a plurality of slitter units 11, said units comprising slitter disks 12 which coact with the front drum. Each slitter disk 12 is carried at one end of a lever 13, to which is also attached

a leaf spring 14. The levers are pivotally supported upon a bar 15 which extends transversely of the machine, and the springs 14 react with the under side of a beam 16 to resiliently retain the disks 12 in operative engagement with the drum 2 during the slitting operation, as illustrated in Fig. 4. In the present instance, the levers 13, which are fulcrumed on the transverse bar 15 as described, are held in adjusted position longitudinally of the bar by means of retainer or spacer members 17 which are releasably clamped to the bar by means of a set screw 18, as illustrated. The lever 13 with the disk 12 and spring 14 may be lifted clear of the bar 15 and of the retainer 17 without releasing the latter from the bar; and by releasing the set screw 18, the lever with its attached elements and the retainer 17 may be removed from the bar as a unit. The structural form and details of the slitter unit 10 form no part of the present invention, and are fully disclosed in my copending application Serial Number 429,087.

The fulcrum bar 15 is supported at the top of an I-beam 19. This beam in turn is supported at each of the opposite sides of the machine upon an eccentric 21, which eccentrics are carried by a rock shaft 22 journaled in the side members of the frame 1, as best illustrated in Fig. 3. Secured to one end of the shaft 22 is a worm wheel 23, and this wheel is operatively engaged by a worm 24 which is rotatably mounted in a lever 25 having a hub 26 which embraces and pivots on the shaft 22. It is apparent that any angular movement of the lever 25 about the axis of the shaft 22 will result in a corresponding angular movement of the worm wheel 23 and of the shaft 22; and that the angular positions of the worm 23 and the lever 25 with respect to each other and with reference to the axis of the shaft 22 may be varied through the worm 24. To this end, one end 27 of the worm shaft is extended and formed for reception of a suitable wrench, by means of which the worm may be turned in the lever. The central web 28 of the beam 19 is extended at each end of the beam beyond the top and bottom flanges, and this extension of the web fits slidably in a slotted rail 29 suitably supported on the frame 1, said rails thereby functioning as guides for the rail movement under actuation of the eccentrics 21, as described above.

The shaft 22 has an arm 31 which extends radially from the shaft for engagement with a stop pin 32 on the frame 1. This pin acts, therefore, to limit the rotational movement of the shaft 22 in one direction. Projecting from the

inner face of the lever 25 is a pin 33, and this pin is adapted for engagement in a recess 34 of a latch 35 which is pivotally secured at 36 to the frame and which is normally maintained by suitable means in a position for engagement with the pin 33 when the lever has been swung around the axis of the shaft 22 to a sufficient extent to afford said engagement. The latch 35 and its recess 34, through the lever 25, establish a limit to the rotary movement of the shaft 22 in a clockwise direction, as viewed for example in Fig. 2. The angular movement of the cams 21 is, therefore, determined by the stop 32 on the one hand, and the latch 35 on the other; and the actual extent of the rotary movement of the cams 21 between the aforesaid established limits will depend upon the relative positions of the lever 25 and the worm wheel 23. With the parts in the operative position illustrated in Fig. 2, for example, it will be apparent that the lever 25 may move through an angle of approximately 180° before the pin 33 will engage the notch 34 of the latch 35; and the cams 21 will be rocked through a like angle. By adjusting the lever 25 angularly with respect to the worm wheel 23 through the medium of the worm 24, as previously described, the maximum angular movement of the lever and, therefore, of the cams 21 may be increased or reduced as desired. In any given position of the lever 25 with respect to the worm wheel 23, the maximum rotary movement of the cams 21 is established, as described above, and will not vary unless or until a subsequent adjustment of the lever 25 with respect to the worm wheel takes place.

The angular movement of the cams 21 determines the extent to which the beam 19 and the slitter units 11 are elevated towards the front drum or platen 2, and since the beam 16 forms a fixed limit stop for the outer terminal ends of the springs 14 of the slitter units, the extent of elevation of the beam 19 also determines the tension of the slitter disks against the drum 2. In practice, therefore, the worm 24 is adjusted to bring the lever 25 into an angular position with respect to the worm wheel 23 such that when the pin 33 of the said lever engages in the recess 34 of the latch 35, the slitter disks will bear with the exact required pressure against the mandrel 2. Thereafter, the lever 25 may be manipulated to retract and elevate the slitter units with assurance that the desired operating tension or pressure of the slitter disks upon the mandrel will remain unchanged. In other words, the pressure of the slitter disks is in effect established and pre-set by adjustment of the worm 24 as described.

It is to be noted that the pin 32 is so positioned, and the arm 31 so arranged with respect to the cams 21, that when the arm engages the pin, the cam is in the position affording maximum clearance between the bar 15 and the drum 2; and that this condition prevails irrespective of the position of the lever or its adjustment through the worm 24 to regulate the slitter tension.

The beam 16, see Figs. 4, 6 and 7, is pivotally supported upon trunnions 37 in the opposite side members of the frame. Secured to one end and to the under side of the beam 16 is a pair of elements 38, 39 which engage opposite sides of a cam 39, this cam being carried at the inner end of a shaft 41 journaled in the frame 1. The outer end of the shaft is provided with a lever arm 42 by means of which the cam may be oscil-

lated. Oscillation of the cam will shift the beam on its pivots 37 between a normal operative position, as shown in Fig. 4, and a retracted position, as shown in Fig. 7. In the normal position, the under side of the beam is in position for engagement with the outer ends of the springs 14 of the slitter units; but in the retracted position, as shown in Fig. 7, the lower edge of the beam is withdrawn from the springs 14, which are thereby freed for vertical movement. With the beam 16 retracted and the beam 19 in its lower position as illustrated, the levers 13 with their slitter disks 12 and springs 14 are readily accessible for withdrawal from the machine.

If the unit as a whole, inclusive of the spacer member 17, is to be removed, this may be accomplished by release of the set screw 18 and by subsequent lateral tipping movement accompanied by elevation of the unit from the fulcrum bar 15. The units may be correspondingly readily applied to the fulcrum bar. It will be understood that with the beam 19 in the depressed position, the lever 13 may be adjusted angularly on the fulcrum 15, so that the outer end of the spring 14 is depressed to a position permitting return of the beam 16 to the normal position overlying the spring; and subsequent elevation of the beam 19 through the medium of the eccentrics 21 will carry the slitter units to their operative positions, as shown in Fig. 4. It will be noted that the outer end of the spring 14 is provided with an adjusting screw 43 whereby some adjustment of the tension of the spring 14 and the resulting pressure of the slitter disks against the drum 2 may be effected independently of the worm and worm wheel device described above.

Pivoted attached to the frame, one at each side thereof, are bell crank levers 44. Each of these levers is connected through an adjustable link 45 with an arm 46 on a rock shaft 47 journaled in the frame. Secured to one end of the shaft 47 is an arm 48 which carries a roller 49 at its upper end, and this roller projects into the path of the lever 25, so that when the lever is thrown upwardly to elevate the slitter units into their operative positions, the arm 48 by engagement with the lever 25 is shifted from its normal position, as shown in broken lines in Fig. 2, to a position shown in broken lines in Fig. 4. This movement of the lever 48 rocks the shaft 47 and elevates the bell crank levers 44 so as to bring a roller 51 upwardly against the web 5 as the latter passes to the front drum 2. This has the effect of elevating the web between the drums 2 and 3, as shown in Fig. 4, and smooths the web immediately in advance of its contact with the drum 2. Thus the smoothing roller 51 is moved into operative position only at such times that the slitter units may be elevated to their operative positions. It is to be noted that by reason of the fact that the roller 51 is elevated by direct action of the lever 25 when the latter advances into the operative position, and since the operative position of the lever is definitely established by the latch 35, the actuation of the roller 51 and its ultimate position of advancement toward the drums are unaffected by adjustments of the slitter tension through the worm 24.

I claim:

1. In a slitting machine of the type comprising a platen roll, a slitting element coactive with the roll, a support for said element movable to and from the roll, and means actuated by movement of said support for resiliently tensioning the slitting element against the roll; mecha-

nism for advancing and retracting the support with respect to the roll, an actuating member for the mechanism, means operatively associated with said member for establishing a limit to the movement of the support in one direction, means operatively associated with said mechanism and independent of the actuating member for establishing a limit to the movement of the support in the other direction, and means for adjusting the actuating member relatively to the mechanism so as to regulate the extent of the movement of the support within said limits.

2. In a slitting machine of the type comprising a platen roll, a slitting element coactive with the roll, a support for said element movable to and from the roll, and means actuated by movement of said support for resiliently tensioning the slitting element against the roll; cam means for advancing and retracting the support with respect to the roll, a lever for actuating the cam, means on the lever for establishing a limit to the movement of the cam in one direction, means independent of the lever for establishing a limit to the movement of the cam in the other direction, and means for adjusting the lever relatively to the cam so as to regulate the extent of the movement of the cam within said limits.

3. In a slitting machine of the type comprising a platen roll, a slitting element coactive with the roll, a support for said element movable to and from the roll, and means actuated by movement of said support for resiliently tensioning the slitting element against the roll; a shaft, a cam secured to the shaft and operatively associated with the support so as to advance and retract the latter with respect to the roll, a worm wheel secured to the shaft, a lever journaled on the shaft and carrying a worm in mesh with the wheel, a stop associated with the shaft to limit the rotation thereof in one direction, means associated with the lever for establishing a limit to angular movement thereof around the shaft axis in the other direction, and means for actuating the worm to adjust the position of the lever around the worm wheel.

4. In a slitting machine of the type comprising a platen roll, a fulcrum member movable to and from the roll, and a lever fulcrumed on said member and having a slitter element for engagement with the platen roll and a spring for tensioning the said element against the roll; a pivoted member forming an abutment for the spring against which the spring is pressed when the slitter element is against the roll to thereby tension the slitter element, the pivot of said member being located above and substantially in line with the resultant spring pressure, and means for adjusting the said abutment member on its pivot.

5. In a slitting machine of the type comprising a platen roll, a fulcrum member movable to and from the roll, and a lever fulcrumed on said member and having at one side of the fulcrum a slitter element for engagement with the platen roll and at the other side of the fulcrum a spring for tensioning the slitter element against the roll; a member adjustable into the path of said spring as the lever is advanced with the fulcrum member so as to form a tensioning abutment for the spring, and cam means for adjusting said member.

6. In a slitting machine of the type comprising a platen roll, a fulcrum bar paralleling said roll and movable to and from the latter, and one or more levers fulcrumed on said bar and having each a slitter element at one side of the fulcrum

and a spring extending at the other side of the fulcrum for tensioning the slitter element against the roll; a beam paralleling the fulcrum bar and pivotally supported for adjustment selectively into alternative positions, said beam in one of said positions lying in the path of the said springs of the slitter levers as the latter are advanced with the fulcrum bar toward the platen roll, and in the alternative position lying clear of the path of said springs, thereby to facilitate removal of the said levers from the fulcrum bar.

7. In a slitting machine of the type comprising a platen roll, a fulcrum bar paralleling said roll and movable to and from the latter, and one or more levers fulcrumed on said bar and having each a slitter element at one side of the fulcrum and a spring extending at the other side of the fulcrum for tensioning the slitter element against the roll; a beam paralleling the fulcrum bar and pivotally supported for adjustment selectively into alternative positions, said beam in one of said positions lying in the path of the said springs of the slitter levers as the latter are advanced with the fulcrum bar toward the platen roll, and in the alternative position lying clear of the path of said springs, thereby to facilitate removal of the said levers from the fulcrum bar, and a cam operatively connected with said beam for adjusting the latter to said positions.

8. In a slitting machine of the type comprising a platen roll, a slitting element coactive with the roll, a support for said element movable to and from the roll, and means actuated by the movement of said support for resiliently tensioning the slitting element against the roll; mechanism for advancing and retracting the support with respect to the roll, an actuating member for the mechanism movable to and from a predetermined terminal position in advancing and retracting the support respectively, means for adjusting the actuating member relative to the mechanism so as to regulate the operative position of the support when the actuating member is in the said predetermined position, means for directing a web of material to said platen, a smoothing roll for engaging the web in advance of said platen, and means actuated by said member when approaching and leaving said terminal position respectively for advancing and retracting said smoothing roll to and from an operative position with respect to the web.

9. In a slitting machine of the type comprising a platen roll, a slitting element coactive with the roll, a support for said element movable to and from the roll, and means actuated by movement of said support for resiliently tensioning the slitting element against the roll, mechanism for advancing and retracting the support with respect to the roll, said mechanism being adjustable to regulate the fully advanced or operative position of the support, means for directing a web of material to said platen, a smoothing roll for engaging the web in advance of said platen, means for advancing and retracting the smoothing roll to and from an operative position with respect to the web, and means for operatively connecting the support with said advancing and retracting means whereby the said means is actuated to advance and to retract the smoothing roll into and from an operative position respectively at the end of the advance and the beginning of the retractive movements of the support irrespective of said adjustment.

ROBERT McC. JOHNSTONE.
